UNITED STATES PATENT OFFICE.

CHESTER B. HUNTING, OF CLINTON, ILLINOIS.

IMPROVEMENT IN WASHING-MACHINES.

Specification forming part of Letters Patent No. 148,827, dated March 24, 1874; application filed January 30, 1874.

To all whom it may concern:

Be it known that I, CHESTER B. HUNTING, of Clinton, county of De Witt and State of Illinois, have invented certain Improvements in Washing-Machines. The following description, taken in connection with the accompanying plate of drawings hereinafter referred to, forms a full and exact specification, wherein are set forth the nature and principles of the invention, by which the same may be distinguished from others of a similar class, together with such parts thereof as are claimed as new and are desired to be secured by Letters Patent of the United States.

My invention relates to washing-machines; and the nature thereof consists in certain improvements in the construction of the same, hereinafter shown and described.

In the accompanying drawing, which illustrates my invention and forms a part of the specification thereof, corresponding parts being designated by similar letters, Figure 1 is a longitudinal vertical section. Fig. 2 is a detached view of one of the concave rubbers.

In the said drawing, the box, designated A, is water-tight, with beveled ends B, and a water-tight central partition, C. The removable rubber beds D are of such a size as to fit within the receptacles *a*, and are intended to be water-tight, except at their centers, where an

opening, *d*, is located, through which the dirt descends. The vibrating rubber E is rotated upon the shaft F, which is secured to the arms H. The said arms H are pivoted to the inner sides of the box in such a manner as to be allowed to describe the arc of a semicircle. They rest upon the projection I, and support the vibrating rubber over the center of either of the compartments *a*, whichever is to be used.

The advantages of this construction are obvious. The compartments may be used alternately. One of them may be arranged for using a small quantity of water, and the other a large quantity, or one may be arranged for rinsing.

Having thus described the construction and operation of my invention, I claim and desire to secure by Letters Patent—

The combination, with the box A provided with compartments *a*, of the reversible rubber E, shaft F, and arms H, as and for the purposes described.

In testimony that I claim the foregoing I have hereunto set my hand this 3d day of November, 1873.

CHESTER B. HUNTING.
